To all whom it may concern:

Be it known that I, STEPHEN C. HOWARD, a citizen of the United States, and a resident of Providence, in the county of Providence and State of Rhode Island, have originated and produced a new Design for the Backs of Brushes and Like Articles, of which the following is a specification.

My design consists in the representation of clover upon a brush or other article.

This design, it will be observed, consists of a brush-back having thereon a representation of intertwined clover.

A designates the clover-leaf, B designates

the stems, C designates the blossoms, and D designates blades of grass, which are incorporated in the design.

What I claim as my invention, and desire to secure by Letters Patent, is—
